UNITED STATES PATENT OFFICE.

JOHN KELLER, OF HOUSTON, TEXAS.

SASH-LOCK.

1,275,443.

Specification of Letters Patent. Patented Aug. 13, 1918.

Application filed February 18, 1918. Serial No. 217,977.

To all whom it may concern:

Be it known that JOHN KELLER, a citizen of the United States, residing at Magnolia Park, Houston, in the county of Harris and 5 State of Texas, has invented certain new and useful Improvements in Sash-Locks, of which the following is a specification.

This invention relates to new and useful improvements in a sash lock.

10 The object of the invention is to provide a device of the character described by means of which window sashes may be adjusted to any desired position in the window-frame and locked in the said position.

15 A further feature of the invention resides in the provision of a device of the character described which may be readily released from its locked position when it is desired to adjust the window sash.

20 With the above and other objects in view, the invention has particular relation to certain novel features of construction, operation and arrangement of parts, an example of which is given in this specification and 25 illustrated in the accompanying drawings wherein:—

Figure 1, is a front view of a window frame, showing the sashes locked in closed position.

30 Fig. 2, is a front view thereof, showing the window sash locked in open position.

Fig. 3, is a vertical, sectional view taken on the line 3—3 of Fig. 2, and

35 Fig. 4, is an enlarged fragmentary view, of a locking device.

Referring now more particularly to the drawings wherein like numerals of reference designate similar parts in each of the figures, numerals 1, 1, refer to the side members of 40 the window frame, and the numerals 2 and 3 designate the top and bottom members, respectively, of said frame. Mounted in this frame, in the usual manner, are the sashes 4 and 5, which are vertically movable, so that 45 they can be opened and closed.

Attached to the sides of the respective sashes 4 and 5, at their upper and lower ends respectively, are the flexible arms 6 and 7.

The upper and lower ends of these respective 50 arms are secured to the corresponding sashes, and the other ends are free and turned at

right angles thereto, forming the grips 8 and 9. These arms are preferably formed of some suitable metal, and their inner edges are provided with a plurality of slots 10, 55 spaced apart. Projecting inwardly from the side members 1, 1, are the studs 11 and 12, against which the corresponding arms rest, said studs being provided to engage in one of the slots 10 to lock the sash, to which 60 the corresponding arm is secured, in fixed position.

When it is desired to move a sash up or down, the grip 8 or 9 may be taken hold of, and the corresponding arm pulled outwardly 65 to release the slot 10 from the studs seated therein and the sash adjusted to the desired position, and one of the slots 10 again engaged with said stud. Owing to the flexibility of the arms, the slots will engage with 70 said studs automatically when the sash is moved to bring them into alinement.

In order to limit the range of the movement of the free ends of the arms, guards 14 and 15 are provided, said guards being 75 attached to the corresponding side members 1, 1, at one end and the other ends being overturned, as shown in Fig. 3, forming a hook to retain the free ends of the arms 6 and 7 in a desired position and to prevent 80 the lateral movement thereof.

What I claim is:—

In a device of the character described the combination with a window frame of a sash movable therein, a flexible member attached 85 to the sash at one end and whose other end is free and bent over at right angles thereto, said member being provided with slots along one side thereof, an engaging member carried by the adjacent side of the window 90 frame and adapted to engage with said slots to lock the sash in position in the frame and a guard provided to limit the range of movement of the free end of said member.

In testimony whereof I have signed my 95 name to this specification in the presence of two subscribing witnesses.

JOHN KELLER.

Witnesses:

JAS. W. OLIVER,
IRENE BRUNS.
